UNITED STATES PATENT OFFICE.

CLIFFORD CLINTON DUDLEY, OF WALLINGFORD, CONNECTICUT, ASSIGNOR TO H. L. JUDD COMPANY, OF WALLINGFORD, CONNECTICUT, A CORPORATION OF NEW YORK.

DESIGN FOR A RACK.

58,557.

Specification for Design.

Patented Aug. 2, 1921.

Application filed February 21, 1921. Serial No. 446,958. Term of patent 14 years.

To all whom it may concern:

Be it known that I, CLIFFORD CLINTON DUDLEY, a citizen of the United States, residing at Wallingford, New Haven county, Connecticut, have invented a certain new, original, and ornamental Design for Racks, of which the following is a specification, reference being had to the accompanying drawing in which—

The figure is a perspective view of a rack embodying my new device.

What I claim and desire to secure by design Letters Patent is:

The ornamental design for a rack substantially as shown.

CLIFFORD CLINTON DUDLEY.
